MULTITAP ATTACHMENT PLUG

Willard G. Tyler, Albany, Calif.

Application September 16, 1950, Serial No. 12,226

Term of patent 14 years

(Cl. D26—1)

To all whom it may concern:

Be it known that I, Willard G. Tyler, a citizen of the United States, residing at Albany, State of California, have invented a new, original, and ornamental Design for a Multi-Tap Attachment Plug, of which the following is a specification, reference being had to the accompanying drawings, forming a part hereof, wherein,

Figures 3 and 4 are elevations of the plug showing mutually opposite sides thereof.

I claim:

The ornamental design for a multi-tap attachment plug, substantially as shown.

WILLARD G. TYLER.
